The ornamental design for the combined universal connector and cap, as shown and described.

DESCRIPTION

FIG. 1 is a perspective view of the combined universal connector with cap inserted into a medical bag showing our new design;

FIG. 2 is a side elevational view of the combined universal connector and cap, all sides being equal;

FIG. 3 is a top plan view thereof;

FIG. 4 is a bottom plan view thereof;

FIG. 5 is a perspective view of the combined universal connector and cap in a detached mode;

FIG. 6 is a bottom plan view of the cap, the connector not being shown for clarity of illustration;

FIG. 7 is a side elevational view of the universal connector;

FIG. 8 is another side elevational view of the universal connector;

FIG. 9 is a top plan view of the connector; and,

FIG. 10 is a bottom view of the connector;

The cap has been omitted from FIGS. 7 through 10 for clarity of illustration.

The medical bag shown in broken lines in FIG. 1 is for illustrative purpose only and forms no part of the claimed design.
